UNITED STATES PATENT OFFICE.

JACOB S. BAUGHMAN, OF BURLINGTON, IOWA.

DOWN-SPOUT FILTER.

SPECIFICATION forming part of Letters Patent No. 540,940, dated June 11, 1895.

Application filed February 19, 1895. Serial No. 539,001. (No model.)

To all whom it may concern:

Be it known that I, JACOB S. BAUGHMAN, a citizen of the United States, and a resident of Burlington, in the county of Des Moines and State of Iowa, have invented certain new and useful Improvements in Down-Spout Filters; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a central vertical longitudinal section through the filter. Fig. 2 is a perspective view of inner filter-box. Fig. 3 is a perspective view of catch-brim. Fig. 4 is a perspective view of modification of outer receptacle. This invention has relation to a filter attachment for down spouts to cisterns, the object being to provide an effective attachment of this character, simple in its construction, and capable of being manufactured at a cost which will make it accessible to families of small means; which can be cleaned in a very short time and operated with very little expense for material, and which can be attached to any down spout at any place, regardless of ground space.

With these objects in view the invention consists in the novel construction and combination of parts, all as hereinafter described, and pointed out in the appended claims.

Referring to the accompanying drawings, the letter A designates the outer case or receptacle of the filter, and a its hinged cover or lid. B designates the down spout connection, and C is the discharge of said case or receptacle.

b indicates straps for hanging the filter and which may be attached at any point to suit the down spout.

E designates an inner filter box having a perforated bottom e, and stirrup feet e' which hold it off the bottom of the outer receptacle. The box E is placed in the case A through the opening in the top thereof, and is then pushed back underneath the down spout.

g is a catch hook for the lid or cover a and h, h, are drop handles riveted to the inside of box E.

F is a catch brim which is arranged to fit over the outside of the top of box E. This brim may be made by crimping a piece of sheet metal over a wire frame of the same size and shape as that forming the top of box E. Attached to the lower inner edge of the brim are hooks f for the purpose of supporting the catch sack G.

p, p, are wires which are fastened to the inside of the brim wire, and which with bottom wires p' form a depending frame to hold the sack in position and permit of free draining. This sack is made of cheese cloth, or other suitable material and of the proper size to fit the catch brim.

In preparing the filter for work, the box E is filled with charcoal to a point sufficiently below its upper edge to admit the sack G and the frame of the catch brim. The sack is then fastened on the hooks f on the lower edge of the brim with its bottom resting on the bottom wires p', and the brim put in place. Box E is then placed in receptacle A, and pushed back under the down spout.

The filter should be cleaned after every shower—that is, the catch brim with the sack should be removed, and the sack cleaned, washed, and aired. The box E should be placed in the sun to dry the coal before being replaced for the next shower. This gives new and better work from the coal and the latter is made to last for a longer time, and need not be removed oftener than once in six months or a year.

The receptacle A and filter box E are preferably made of galvanized iron. The holes in the perforated bottom are usually made about three-eighths of an inch in diameter, and from three-eighths to seven-eighths of an inch apart.

In Fig. 4 I have shown a modified construction of the outer receptacle A, wherein such receptacle instead of being entirely closed is open on three sides, except at the lower portion A², the cover being hinged to the back in the manner shown. The closed lower portion A² will usually be about six inches deep, and of the proper size to receive the filter box, which is placed therein by raising the cover. This form of the receptacle requires less material to construct, and is in some respects more convenient.

Having thus described my invention, what I claim as new, and desire to secure by Letters Patent, is—

1. The herein described filter attachment for down spouts, comprising an outer case or receptacle into which the down spout discharges, an inner filter box E removably supported in said receptacle, and having a perforated bottom, and a catch brim removably fitted to the open upper end of said filter box and having a depending open frame and a catch sack supported by said frame of the upper portion of said box, substantially as specified.
2. The herein described filter attachment for down spouts to cisterns, said attachment comprising the outer case or receptacle A, into which the down spout opens, and from which

the water is discharged into the cistern, said box having a hinged cover and supporting straps, an inner filter box E, removably supported in said receptacle and having feet which hold it away from the bottom thereof, said box having a perforated bottom, a catch brim removably fitted to the upper portion of said box, and having sack-supporting hooks, an open wire frame attached to said brim, and fitting inside of said box, and a catch sack attached to said hooks and supported in said frame, substantially as specified. 30

In testimony whereof I affix my signature in presence of two witnesses.

JACOB S. BAUGHMAN
